Original application April 25, 1930, Serial No.
447,379. Divided and this application July 20,
1935, Serial No. 32,442

16 Claims. (Cl. 180—68)

This invention relates to automobile radiator shells, and more particularly to a composite shell assembled from a plurality of initially separate parts, thereby enabling distinctive, ornamental features to be introduced into the structure.

Ordinarily radiator shells are formed as integral units by stamping or die pressing them from sheet material in the form of pans and thereafter removing the bottoms of the pans and 10 any other unwanted portions as waste material. It is frequently desirable, however, to incorporate in a radiator shell more or less ornamental sections which perhaps cannot be economically produced in the die pressing operation by which the 15 remainder of the shell is formed or which may necessitate the use of different metals, different shaping or forming operations, or use of other characteristically different materials.

The present radiator shell, which comprises 20 multiple interconnected elements may be produced with minimum waste of materials and the elements may be variously formed of dissimilar materials if desired, which when united affords a radiator shell of pleasing highly ornamental 25 appearance at minimum costs of production.

The object of the invention is to provide a 30 radiator shell which may be economically and conveniently manufactured with minimum waste of material, and which will permit a wide range of variation of design with minimum change of production dies.

A further object of the invention is to provide 35 a radiator shell comprising an assembly of initially separately formed portions which are interconnected into a unitary structure after being shaped.

A further object of the invention is to provide 40 a radiator shell in which are incorporated ornamental or other portions differing characteristically from adjacent portions of the shell.

With the above primary and other incidental 45 objects in view, as will more fully appear in the specification, the invention consists of the features of construction, the parts and combinations thereof, and the mode of operation, or their equivalents, as hereinafter described and set forth in the claims.

Referring to the accompanying drawing where- 50 in is shown the preferred but obviously not nec-
essarily the only form of embodiment of the in-
vention Fig. 1 is a perspective view of the assem-
bled radiator shell forming the subject matter
hereof. Fig. 2 is a top plan view thereof. Fig. 3
is a perspective view of a pair of side elements
55 of the shell disposed in their ultimate relation to

each other before being interconnected by an intermediate ornamental panel or coupling section. Fig. 4 is a perspective view illustrating one method of producing the side elements of the radiator shell in conjoined relation to minimize production costs. Fig. 5 is a transverse sectional view on line 5—5 of Fig. 4. Fig. 6 is a perspective view illustrating the side members of the shell separated from each other and after removal of waste material incident to the die 10 pressing operation. Fig. 7 is a transverse sectional view of the two side elements on line 7—7 of Fig. 6. Fig. 8 is a sectional perspective view on line 8—8 of Fig. 3.

Like parts are indicated by similar characters 15 of reference throughout the several views.

The radiator shell, forming the subject matter 20 hereof, as illustrated in Fig. 1 comprises two transversely contoured inverted substantially L shaped side members 1—1 arranged in a reversely disposed relatively spaced relation and terminally interconnected one with the other into a unitary structure by an interposed ornamental panel or coupling section 2. This ornamental 25 intermediate section 2 may be of material differing from that of the side members 1 or it may be shaped or treated by production methods different from the die pressing operation by which the side elements 1 are preferably formed. The side 30 elements 1 produced from the same forming die may be assembled with coupling sections or ornamental panels 2 of various different designs to produce a variety of radiator shells having different ornamental appearances.

While the side elements 1 may be separately 35 formed in different right and left forming dies, for economy of production and to facilitate manufacture, these side elements are preferably simultaneously formed in pairs from a single blank at the same forming operation.

The sheet metal blank from which the right and left side are conjointly formed comprises an oblong strip of material of relatively small dimensions having a width slightly greater than double the width of the metal of the finished side 45 members of the shell plus the necessary area of material for holding the sheet while it is being die pressed to the required shape.

The length of the blank is substantially that of one of the side elements plus the necessary 50 terminal gripping area for engagement of the blank holder of the forming die. By thus forming the right and left side elements of the radiator shell simultaneously from a single blank by one die pressing operation, not only is great saving 55

effected in the material required and the waste thereof reduced to minimum, but the draw or stretch of the material is equalized during the forming operation, and the draw of each section is opposed to that of the opposite section, which has been found to be quite advantageous. After conjoint formation of the right and left side elements 1 they are longitudinally severed one from the other and trimmed to remove as waste material the blank holding areas by which the sheet is gripped during the forming operation. While the separate side elements thus produced may be directly interconnected one to the other by welding or otherwise, providing they are sufficient size, they are preferably interconnected with the intermediate ornamental panel or coupling member 2. While for illustrative purposes there is shown in the drawing a very simple form of radiator shell of substantially inverted U shape, opened at the bottom, it is to be understood that the lower end of these side elements 1 may be interconnected by a transverse portion at the bottom or they may be initially formed with inwardly extending arms which may be united directly one to the other or interconnected by an intermediate coupling portion analogous to the interposed ornamental sections 2. Being mere duplication such bottom connection has not been shown.

30 Preparatory to the forming operation the sheet metal blank is initially bent into curvilinear form as at the point 3 and again bent reversely as at 4 to adapt it to the shape of the forming die. This initial bending of the sheet metal blank provides work holding areas 5 and 6 located at the ends of the oblong sheet and similar work holding areas located at the longitudinal margins thereof. These areas to be gripped, particularly those in the region of maximum draw are engaged between coating ribbed and grooved matching areas of the blank holder to prevent undue flow of the metal from the edges of the blank into the central area as the drawing operation is effected. Not only are the side elements 1 substantially L shaped in their longitudinal aspect but the cross section of each of these shell elements is approximately L shaped. The formation of the reverse contours of the right and left side elements from a single sheet of material produces a channel shaped formation and insures a uniform draw of the metal, particularly at the region of maximum depth which occurs at the longitudinal bend of the side elements. Such formation of the two side members of the radiator shell having like but oppositely contoured shapes at the same time enables displacement of the like amounts of material in opposite directions and thus produces a uniform stretch of the metal and a balanced resistance pressure upon the die. When the pair of side elements have been conjointly formed as illustrated in Fig. 4 the holding areas 5, 6, 7, and 8 are trimmed therefrom and the formed structure is cut along a medial line thereby producing the two concave L shaped forms indicated at 15 and 16 in Fig. 6.

70 The edges 17 of the parts 15 and 16 may then be shaped if desired to form a ledge 18 along which the shell makes contact with the face of the radiator core when assembled therewith. The separated parts 15 and 16 are welded or otherwise terminally united with the intermediate ornamental panel or coupling section 2 to form the complete radiator shell. This intermediate coupling member is ordinarily provided with the

usual filler opening 21 through which water may be introduced to the completed radiator.

While the simultaneous production of right and left side elements at a single operation greatly facilitates the manufacture and minimizes cost of production and has a further advantage of affording equalized or uniform draw and die resistance pressure, it is to be understood that the members 15 and 16 shown in Fig. 6 may be independently formed in separate dies and subsequently united with an intermediate ornamental panel or coupling section 2 in the relation illustrated in Figs. 1 and 2.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

This application is a division of application, Serial Number 447,379 filed April 25, 1930.

Having thus described the invention, what is claimed is:

1. A radiator shell comprising two relatively spaced substantially half portions of inverted L shaped channel formation and an intermediate 40 separately formed spacer member to which the separated portions of the L shaped channel formation are terminally connected into an integral U shaped body.

2. A radiator shell including two sections, each 45 including integral vertical and transverse portions of channel formation, said sections being disposed in reverse relation in a common plane with like sides of the portions extending in the same general direction in substantially parallel 50 spaced relation with their transverse portions extending in reverse relation, one toward the other, and a separately formed spacer member interposed intermediate corresponding ends of the top portions and to which said portions are fixedly 55 united.

3. A radiator shell comprising two sections of channel formation each including integral vertical and horizontal portions disposed in reverse relation in a common plane, an ornamental panel 60 overlapping the adjacent ends of the respective sections and terminally interconnecting one to the other with the vertical portions extending in substantially parallel relation in the same direction.

4. A composite radiator shell comprising a plurality of initially separate elements interconnected into a unitary structure and including right and left integral curvilinear channel side elements arranged in oppositely disposed relatively spaced relation, and an interposed separately formed ornamental body to which the opposite side elements are terminally interconnected to form an integral radiator shell assembly.

5. A composite radiator shell assembly includ-

ing side portions terminating at the top of the shell in inwardly directed relatively spaced portions, and a separately formed ornamental insert interposed between the spaced ends of said side portions and fixedly united thereto to form a complete radiator shell unit.

5 6. A composite radiator shell assembly including two side elements shaped into channel shaped curvilinear formation and terminating at the top 10 of the shell in inwardly directed relatively spaced top portions, and a separately formed ornamental coupling section interposed between the relatively spaced inwardly directed top portions of the side elements and fixedly united thereto to form 15 a unitary structure.

7. A composite radiator shell assembly comprising two elements, each including integral vertical and transverse portions shaped into curvilinear channel formation and having transverse 20 portions inwardly directed and connected one to the other at the top of the shell, and a separately formed ornamental section mounted 25 medially of the top of the shell and fixedly connected to said inwardly directed portions to form a unitary structure.

8. A composite radiator shell assembly, comprising two half portions each including integral complementary side and top portions having their upper ends inwardly directed at the top of 30 the shell and a separately formed ornamental section mounted in a medial position at the top of the shell common to and fixedly attached to the said inwardly directed top portions to form a unitary structure.

35 9. A composite radiator shell assembly comprising two curvilinear channel shaped sections, each including integrally formed vertical and transverse portions disposed in reverse relation in a common plane with the transverse portions inwardly directed and terminally connected one to the other with like vertical portions extending in substantially parallel spaced relation, and a separately formed ornamental section mounted at the juncture of the curvilinear channel shaped 40 45 portions and fixedly united therewith to form a unitary structure.

10. A composite radiator shell assembly comprising two like elements, each including integrally connected channel shaped side and top portions arranged in reverse relation with their top 50 portions connected one to the other and a separately formed ornamental section disposed medially of the connected top portions and fixedly attached thereto to form a unitary structure.

55 11. In a composite radiator shell assembly, opposite complementary side portions and transverse reversely disposed top portions formed integrally with the respective side portions, means

for holding the reverse top portions in immovably fixed relation with each other, said assembly including a separately formed ornamental panel located medially of the relatively fixed top portions of the shell assembly.

12. In a composite radiator shell assembly, opposite complementary relatively spaced parallel side portions and transverse top portions formed integrally with the respective side portions, means for uniting the top portions to hold the same in 10 fixed relation with each other, said means including a separately formed ornamental panel overlapping the adjacent ends of the respective top portions.

13. A radiator shell including two parallel 15 spaced side portions and complementary transverse half top portions formed integrally with the respective side portions and overhanging the space therebetween, and an ornamental panel extending vertically over the front face of the 20 shell and thence rearwardly over the top thereof, the opposite margins of which extend in overlapping relation with the complementary halves 25 of the top portion to which the panel is fixedly attached.

14. A radiator shell including two parallel spaced side portions and complementary transverse half top portions formed integrally with the respective side portions and overhanging the space therebetween, and an ornamental panel 30 35 extending transversely over substantially the entire width of the top portion and also longitudinally thereof in opposite directions from the medial line of the shell in overlapping relation with the complementary halves of the top portion to which the panel is fixedly attached.

15. A radiator shell comprising two complementary channel shaped curvilinear sections, each including integral, vertical and transverse portions, the curvilinear sections being reversely 40 disposed in a common plane and terminally connected one to the other to form a continuous integral radiator shell including an ornamental section affixed to the shell in symmetrically disposed relation to the respective sections thereof. 45

16. A composite radiator shell including a pair of complementary channel shaped curvilinear die pressed sections, each comprising integral, vertical and transverse portions, the sections being arranged in reversely disposed relatively fixed relation in a common plane and terminally interconnected one with the other to afford a unitary symmetrical radiator shell.
